UNITED STATES PATENT OFFICE.

NOAH B. CANNADY, OF EUREKA, KANSAS.

WEATHER STRIP.

Application filed October 6, 1921. Serial No. 505,802.

To all whom it may concern:

Be it known that I, NOAH B. CANNADY, a citizen of the United States, residing at Eureka, in the county of Greenwood and 5 State of Kansas, have invented a new and useful Weather Strip, of which the following is a specification.

This invention has reference to weather strips, and more particularly to sectional 10 metallic weather strips wherein one section may move within the opposed section to provide a fluid-tight connection therebetween.

The primary object of the invention is 15 to provide a metallic weather strip constructed in a manner to exclude moisture and air, the weather strip embodying opposed elements adapted to be moved into close engagement.

20 Another object of the invention is to provide a weather strip of this character which may be readily and easily applied to a sash, it being necessary to make only minor changes in the sash construction to install a 25 strip.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without 35 departing from the spirit of the invention.

Referring to the drawings:—

Figure 1 is a vertical sectional view 40 through a sash and its frame, the same being supplied with a weather strip constructed in accordance with the present invention.

Figure 2 is a sectional view taken on line 2—2 of Figure 1.

Figure 3 is taken on line 3—3 of Figure 1. 45 Referring to the drawings in detail, the frame is indicated generally by the reference character 5, and is shown as formed with the usual guide strips 6 and 7, there being provided a central guide strip 8 disposed between the sash members, to hold the same in spaced relation with each other.

The frame also includes a sill 9 to which is secured a metallic plate 10 that has an upward extending flange 11 terminating in a

spaced downward extension 12, the space 55 between the body of the flange and downward extension being designed to accommodate the upwardly extending right angled portion 13 of the plate 14 which is secured to the sill as by means of the screws 60 15. These plates 10 and 14 extend across the entire width of the frame to guard the window throughout its entire width.

Carried by the lower sash which is indicated by the reference character 16 and disposed adjacent to the outer side thereof is a transversely extending plate 16 which is designed to move over the downward extension 12 of the flange 11 forcing the downward extension into close engagement with 70 the portion 13 of the plate 14, thereby insuring an air-tight connection between the elements of the weather strip. It might be further stated that the lower rail of the sash 16 is cut away as at 17 to provide a 75 clearance for the upwardly extending elements of the weather strip.

As clearly shown by Figure 1 of the drawings, the upper rail of the lower sash is inclined as at 18 to cooperate with the inclined surface 19 of the lower rail of the upper sash 20, the lower rail supporting a transversely extending flanged plate 21 formed of flexible metal, a portion of the plate being turned downwardly to contact 80 with the inclined edge 18 of the lower sash, and insure a fluid-tight connection between the adjacent edges of the upper and lower sashes.

The upper sash also embodies an upper 90 rail 22 to which is secured a flexible metallic plate 23 formed with a downwardly extending portion 24 that contacts with the downwardly extending flange 25 formed on the plate 26, the latter plate being carried by 95 the window frame. Thus it will be seen that since these contacting plates are formed of flexible metal, a binding action will be set up therebetween to insure an air-tight connection.

In order that an air-tight connection may be provided between the sashes and the side bars of the casing or window frame, plates 27 are provided, the same being secured to the sashes as by means of the screws 28. 100 These plates are formed with right angled portions 29 that move between the opposed portions of members 30 that are carried by 105

the frame as clearly shown in Figure 2 of the drawings.

While I have shown and described a construction for providing an air-tight connection between the side rails of the sashes at one side and the frame in which the same move, it is to be understood that this construction is duplicated with both sashes.

Having thus described the invention, 10 what is claimed as new is:—

In a window construction comprising a sill, and a sash having a rabbeted lower rail, a plate secured to said sill and having an upwardly extending flange formed integral 15 therewith, a plate secured to said sill cooperating with the first mentioned plate and

having an upwardly extended flange terminating in a downwardly extended portion disposed in spaced relation therewith to provide a pocket for the first mentioned flange 20 and a plate secured to said sash rail rail and cooperating with said rabbet to form a channel, said flanges adapted to be received in said channel and frictionally engage the walls thereof. 25

In testimony that I claim the foregoing as my own, I have hereto affixed my signature in the presence of two witnesses.

NOAH B. CANNADY.
